UNITED STATES PATENT OFFICE.

CHARLES WAGNER, OF GRANTWOOD, NEW JERSEY, AND AUGUST HORMEL, OF NEW YORK, N. Y.

LITHOGRAPHIC PRESS.

1,120,770.

Specification of Letters Patent. Patented Dec. 15, 1914.

Application filed January 15, 1914. Serial No. 812,172.

To all whom it may concern:

Be it known that we, CHARLES WAGNER, a citizen of the United States, residing at Grantwood, county of Bergen, and State 5 of New Jersey, and AUGUST HORMEL, a citizen of the United States, residing at New York city, county and State of New York, have invented certain new and useful Improvements in Lithographic Presses, of 10 which the following is a specification.

This invention relates to a rotary lithographic press of novel construction by means of which the desired number of prints may be produced in a simple, quick 15 and reliable manner.

The press comprises essentially a cylinder about one moiety of the circumference of which is surrounded by a removable lithographic plate which is alternately inked and 20 damped. After the plate has been properly inked, the matter to be reproduced, is applied to a transfer roller, the outer diameter of which equals one half of that of the plate-covered cylinder. While the plate is subsequently damped, the design, etc., applied to 25 the transfer roller is printed upon a sheet of paper or other material, the proper feeding of said sheet being automatically regulated by the machine.

30 The invention further comprises other novel features as fully brought out in the appended specification and claims.

In the accompanying drawing: Figure 1 is a side elevation of a lithographic press, 35 embodying my invention, Fig. 2 a vertical longitudinal section thereof, Fig. 3 an enlarged cross section on line 3—3, Fig. 2, Fig. 4 a cross section on line 4—4, Fig. 2, and Fig. 5 a plan of the paper feeding 40 means.

In a pair of standards 10, there is journaled a shaft 11 provided with fast and loose pulleys 12, 13. Upon shaft 11 is firmly mounted a drum or cylinder 14, adapted to 45 receive the lithographic plate or sheet 15, that encircles about one moiety of the circumference of the cylinder, as clearly illustrated in Fig. 3. The other half of cylinder 14 is surrounded by a curved plate 16 that is permanently secured to the cylinder and constitutes a support for the paper sheet during 50 the printing operation proper. In order to hold the parts 15, 16 in position, cylinder 14 is provided with a pair of longitudinal dia-

metrically opposed tapering recesses 17^a, 55 each recess being adapted for the reception of a wedge-shaped key 17. Keys 17 are secured to cylinder 14 by screws 18 and, by engaging the inwardly bent edges 19 of plate 16 hold the latter securely in position. The 60 lithographic sheet 15 is also provided with inwardly bent edges 20 which are adapted to be slid through longitudinal passages 21 of cylinder 14 where they are clamped to keys 17 by a plurality of eccentrics 22. The 65 latter are firmly mounted on a pair of longitudinal spindles 23 journaled in cylinder 14, the outer eccentrics of each spindle being provided with inwardly extending fingers 24 that are connected to the cylinder 70 by springs 25. It will thus be seen that in order to apply a lithographic sheet 15 to cylinder 14, the fingers 24 of each spindle 23 are turned forward to release the eccentrics 22, whereupon the edges 20 of sheet 15 75 are inserted and the fingers are turned back to clamp the sheet to keys 17, the springs 25 retaining the eccentrics in their operative position.

Sheet 15 is adapted to be alternately 80 damped and inked in the following manner: Within suitable guiding means 26 of each of the standards 10 is reciprocably mounted a slide 27 provided with a pair of cam rollers 28 that engage a cam 29 firmly 85 mounted on shaft 11. To one end of each slide 27 is adjustably secured by nuts 30, a rod 31 to which is swiveled at 32, a frame 33. Within frames 33 is hung a damping roller 34 and a moisture distributing roller 90 35, roller 34 being adapted to engage a transfer roller 36 journaled in a fixed arm 37, roller 36 receiving moisture from a supply roller 38 that dips into a water pan 39. To the other end of each slide 27 is adjustably secured by nuts 40 a rod 41 to which is swiveled at 42, a frame 43. Within frames 43 is hung a pair of inking rollers 44 that engage a common ink transfer roller 45 the shaft 46 of which is received within 95 an inclined slot 47 of each frame 43, the inking rollers receiving the usual axially reciprocating movement in any suitable manner (not shown). Roller 45 is adapted to engage a roller 48 journaled in a fixed 100 arm 49 and receiving ink from a supply roller 50 dipping into well 51. The cams 29 are so shaped and set that when the litho-

graphic sheet 15 passes by inking rollers 44, slides 27 are shifted toward the left (Fig. 3) so that these rollers will transfer their ink which they previously received 5 from rollers 48, 50 to said sheet. While the parts are in this position, the moisture transfer roller 36 is engaged by damping roller 34 so that an amount of moisture sufficient for damping is applied thereto.

10. When during the continued rotation of cylinder 14 in the direction of the arrow (Fig. 3), the sheet 15 approaches the damping device, slides 27 are shifted toward the right to thereby bring rollers 34, 35 into 15 contact with sheet 15 so as to properly damp the same, while at the same time, roller 45 is brought into engagement with roller 48, whereby rollers 44 are inked preparatory to the next inking operation.

20. Vertically above cylinder 14 there is arranged a transfer roller 52 which is covered by a rubber blanket 53, the outer diameter of the blanketed roller equaling one half of the outer diameter of the plate-covered cylinder 14. Blanket 53 is firmly clamped to the roller by a wedge-shaped key 54 fitted into a corresponding longitudinal groove 55 and held in position by screws 56 and dowel pins 56^a. These screws and 30 pins engage preferably eyeleted perforations of the overlapping blanket-ends, so that by properly tightening screws 68, the blanket may be secured to the roller under the desired tension. The gudgeons 57 of 35 roller 52 are journaled in slide blocks 58 that are guided along corresponding ways 59 of standards 10, and are engaged by lifting springs 60. To each block 58, there is pivoted at 61 one member 40 62 of an adjustable link, the other member 63 being fulcrumed to a wrist pin 64 of a rock shaft 65. Members 62, 63 are provided with right and left hand threads that are engaged by a turn buckle 66. Shaft 45 65 is mounted vertically above roller 52 and is provided with a handle 67, so that by properly manipulating the latter, roller 52 may be lowered into engagement with cylinder 14, or springs 60 may be permitted 50 to raise the roller off said cylinder. Roller 52 is permanently intergeared with cylinder 14 by means of a pair of gear wheels 68, 69 secured to the ends of cylinder 14 and roller 52 respectively, so that the roller 55 performs exactly two revolutions while the cylinder makes one revolution.

In a direction substantially tangential to the top of cylinder 14 extends a slightly inclined table 70, the latter being provided 60 with a cut-out 71 for exposing the cylinder. The sheet 72 to be printed is placed upon table 70 and is checked in its advance by means of movable stops 73 until the lithographic sheet 16 has advanced to a position to warrant an advance of said sheet

for printing. For withdrawing stop 73 from sheet 72 and feeding the latter, a shaft 74 is provided which extends in parallelism with roller 52 and is hung in suitable bearings 75. Shaft 74 carries a pair of relatively fixed elbow levers 76, the forward arms of which are connected by a rotatable spindle 77. To the latter is keyed a plurality of axially adjustable paper feed rollers 78 which rollers are adapted to be lowered upon a spring-influenced friction roll 79, accommodated within a corresponding tapering slot 80 of table 70. In the rear arms of elbow levers 76 are journaled arbors 81, upon which are firmly mounted cam rollers 82 adapted to engage substantially semicircular cams 83 flanking toothed wheels 68. Rollers 82 are, by pinions 84, 85, 86, intergeared with the paper feed rollers 78 so that the movement is positively transmitted from the cam rollers to the paper feed rollers. Stops 73 are firmly secured to blocks 87 that are in turn fastened to shaft 74. The rear arms of levers 76 are engaged by springs 88 that raise rollers 78 off roll 90 79 and at the same time lower stops 73 into the path of sheets 72 whenever the cam rollers 82 are out of engagement with cams 83.

It will be seen that when a lithographic plate 15 has been properly attached to cylinder 14, and the press is started, said sheet will be alternately damped and inked owing to the reciprocative movement of slide 27. Before printing, handle 67 is depressed to lower roller 52 so that when the inked sheet 100 passes underneath said roller, the matter to be lithographed is transferred to the rubber blanket 53 of roller 52. As soon as this operation has been about completed (the exact time depending upon the location of 105 stops 73 relatively to that of cylinder 14) cams 83 engage rollers 82 to tilt levers 76, thereby withdrawing said stops from the paper sheet 72, which had previously been fed to said point by hand, and at the same 110 time lowering feed rollers 78 upon roll 79, to advance said paper sheet. While the lithographic matter is thus transferred from blanket 53 to sheet 72, the lithographic plate 15 is damped by rollers 34, 35 prior to the 115 next inking operation. Upon the completion of the printing of sheet 72, cams 83 clear rollers 82 to permit springs 88 to lift rollers 78 off roll 79 and lower stops 73, against which the next sheet to be printed, 120 is placed by hand, whereupon the operation described is repeated.

We claim:

1. A lithographic press comprising a rotatable cylinder, a curved lithographic plate adapted to be removably secured thereto and encompassing approximately half the circumference thereof, a damping roller, an inking roller, and common means for simultaneously reciprocating the damping roller 130

and the inking roller in the same direction, thereby alternately bringing said rollers into contact with said plate.

2. A lithographic press comprising a rotatable cylinder, a curved lithographic plate adapted to be removably secured thereto and encompassing approximately half the circumference thereof, a slide, damping rollers and inking rollers carried thereby, and means for reciprocating the slide, whereby the damping rollers and inking rollers are alternately brought into engagement with the lithographic plate.
3. A lithographic press comprising a rotatable cylinder, having a pair of diametrically opposed longitudinal grooves, a curved
- paper supporting plate encircling approximately one half of the circumference of said cylinder and extending into the grooves thereof, a pair of keys seated within the cylinder-grooves and adapted to permanently hold the plate to the cylinder, a lithographic plate encircling approximately the other half of the cylinder-circumference and also extending into the cylinder-grooves, and spring-influenced eccentrics adapted to clamp said lithographic plate to the keys.

CHARLES WAGNER.
